UNITED STATES PATENT OFFICE.

THOMAS SPACIE, OF BLUE ISLAND, ILLINOIS.

ROLLER-SKATE.

1,208,681.

Specification of Letters Patent. Patented Dec. 12, 1916.

Application filed April 22, 1916. Serial No. 92,992.

To all whom it may concern:

Be it known that I, THOMAS SPACIE, a citizen of the United States, and a resident of Blue Island, in the county of Cook and State of Illinois, have invented a new and Improved Roller-Skate, of which the following is a full, clear, and exact description.

This invention relates to games and toys and has particular reference to skates made 10 chiefly of sheet metal.

Among the objects of the invention is to improve this class of devices whereby they may be cheapened in construction without materially affecting their reliability.

15 With the foregoing and other objects in view, the invention consists in the arrangement and combination of parts hereinafter described and claimed, and while the invention is not restricted to the exact details of 20 construction disclosed herein, still for the purpose of illustrating a practical embodiment thereof reference is had to the accompanying drawings, in which like reference characters designate the same parts in the 25 several views, and in which—

Figure 1 is a vertical longitudinal section on the line 1—1 of Fig. 2; Fig. 2 is a front elevation; and Fig. 3 is a perspective detail view of the anchor device.

30 Referring now more particularly to the drawings wherein is shown the front portion only of my improved skate, I provide a sole plate 10 slightly curved at its front end to correspond to the usual form of the shoe or 35 boot sole, but having downwardly projecting strengthening side flanges 11. The flanges are comparatively narrow or shallow for economy of material, but provide ample strength or stiffness for the sole plate where 40 the maximum strain occurs. The sole plate is provided with a pair of guide studs 12 along which a pair of claws 13 are guided for movement toward and from each other transversely of the sole plate by means of a 45 right and left screw 14 of well known form, the screw acting through downwardly projecting lugs 13' of the claws.

The rollers 15 are journaled in any suitable manner upon an axle 16 extending 50 transversely through a cradle member 17 including a tubular sleeve 18 having direct engagement with the axle. The body of the cradle receives a cushion 19 of some suitable resilient material, the same being held between front and rear parallel lugs 20 having 55 alined holes through which a pivot pin 21

projects, thereby locking the cushion in place also. The pin at its middle portion is provided with projections 21' which limit the downward or rearward movement of the 60 pin with respect to the cradle. The upper end of the pin constitutes a head 22 having a spherical concavity in the extreme end projecting into a groove 23 formed around the central portion of the screw 14. This pin, 65 therefore, serves not only as a connecting pivot pin for the cradle, but also as a brace for the clamping claws through the screw. As noted in Fig. 1, the head 22 projects well around one half of the screw. 70

At 24 is indicated a cap fitted over the upper surface of the cushion 19. This cap is provided with a pair of slots 25 adjacent its upper and lower ends.

The main support between the sole plate 75 and the cradle consists of a pair of pedestal members 26 and 27. The member 26 is riveted or otherwise rigidly secured at its upper end at 28 to the bottom of the sole plate and has an ear 29 projecting downwardly through the upper slot 25 of the cap plate 24 just in front of the cradle lug 20. The pin 21 projects through a hole in this lug 29 and the projections 21' bear directly against the front face thereof. The member 80 26 is thus locked to the cradle, but a limited amount of lateral rocking movement around the pin 21 is permitted.

The other pedestal plate 27 is a channel structure and is riveted or otherwise secured 90 at 30 to the sole plate at its upper end. The lower end of this plate constitutes a lug 31 extending downwardly through the other slot 25 and having the lower end of the pin 21 extending therethrough as clearly 95 shown in Fig. 1. This pedestal structure is very cheap in its make-up, being stamped and formed from sheet metal, but is of maximum rigidity.

The heel portion of the skate is not shown, 100 but a rib 32 that connects the sole and heel portions is indicated, and the means for securing the front end of the rib and constituting a part of the novel features of this invention are illustrated. The main securing 105 means for the rib is an anchor piece 33 shown in detail in Fig. 3, the same being stamped from sheet metal and having a web 34 lying against the bottom surface of the rib and provided adjacent its front end with 110 a transverse slot 35. At the rear end the anchor plate is cupped or depressed at 36

to receive a nut 37 through which a set screw 38 projects and bears against the bottom of the rib to determine the relative lengthwise adjustment of the rib and sole plate. The 5 web of the pedestal member 37 has an upwardly projecting central lug 39 which fits into the anchor slot 35. The side webs or flanges 40 of the anchor member extend upwardly and thence laterally forming wings 10 41 through which the rear portion of the anchor is clamped rigidly at 42 to the rear end of the sole plate. These side flanges 40 and ears form a rigid stable guide for the rib, preventing all tendency to lateral twisting 15 or vibration without the necessity for any downwardly projecting parts or flanges at the extreme rear edge or end of the sole plate, an important element of simplicity and economy in construction.

20 I claim:

1. In a roller skate, the combination with a sole plate, a pair of clamping claws 25 slideable toward and from each other along said plate, and a right and left screw co-operating with said claws to control their operation, said screw having a circumferential groove 30 at its central portion, of a pedestal secured to the bottom of the sole plate, a pair of wheels, a cradle connected to the wheels and co-operating with the lower end of the pedestal,

and a pivot pin extending through the pedestal and cradle effecting the pivotal connection, said pivot pin having means projecting laterally therefrom to limit the extent of projection through the pedestal and 35 cradle and having an arc-shaped head at its upper end extending into said groove and serving to brace said screw.

2. In a roller skate, the combination of a sole plate having a flat flangeless rear end, a 40 longitudinal rib adjustably connected to the sole plate and extending rearwardly therefrom, and an anchor member for determining the adjustment of the rib, said anchor member being formed of sheet metal and 45 comprising a horizontal web and upwardly projecting side flanges embracing the sides of the rib and preventing lateral movement of the rib and a pair of wings extending laterally from the upper edges of the flanges 50 for positive rigid connection to the sole plate, and a clamping screw carried by the anchor member and bearing upwardly against the bottom of the rib, substantially as set forth.

THOMAS SPACIE.
